CONTAINER

John M. Hothersall, Brooklyn, N. Y., assignor to
 American Can Company, New York, N. Y., a
 corporation of New Jersey

Application April 12, 1938, Serial No. 201,599

6 Claims. (Cl. 220—1)

The present invention relates to labelled including lithographed metallic containers or cans and has particular reference to can body and in some cases also can end construction which allows 5 for the usual can closing processes but which functions to disrupt the can wall or walls thereby destroying the usefulness of the can when tampered with, thus preventing opening, substitution of the can contents, resealing of the can using 10 the same label and insuring a single use for that labelled container. In some respects the present invention is an improvement upon the Fred G. Foss application Serial Number 69,983 filed March 20, 1936, for container.

Like the Foss invention one outstanding use for the present tamper-proof invention is in the canned lubricating oil field where oil companies have been bothered with certain nefarious practices 20 of bootlegging and substitution of oil. Such substitution is largely directed to cans having nationally known labels usually lithographed cans which have been opened, the oil removed, other oil replaced in the can which was then resealed without in any way changing the label. This 25 illicit merchandising is by no means confined to the oil trade but in any instance a poorer product has been palmed off on an innocent public who judging from the label, which does not rightfully belong, forms a mistaken judgment of the 30 contents of the can thus resulting in lasting damage to the lawful owner of the label.

An object of the present invention is the provision of a labelled container or can so formed that a part of the can will break and prevent re- 35 conditioning and re-use when an attempt is made to take out the original can contents and to substitute and seal into the can some other contents.

Another object of the invention is the provision of a labelled can of the double seam type having a 40 body wall in which is cut a plurality of parallel score lines located in and adjacent the edges of the body, the scored body wall breaking through or fracturing when and if the seam is disturbed, as when the scored section of the body wall is 45 flexed back and forth as would be unavoidable where an attempt is made to substitute other contents or other can parts.

A further object of the invention is the provision of a can of this nature having in addition a 50 scored portion in the can cover wall.

Numerous other objects and advantages of the 55 invention will be apparent as it is better understood from the following description, which, taken in connection with the accompanying drawing, discloses a preferred embodiment thereof.

Referring to the drawing:

Figure 1 is a perspective view of a sealed lithographed can embodying the present invention;

Fig. 2 is a plan view of a can body blank from which a can body may be subsequently formed, 5 this view showing the blank from the inside;

Fig. 3 is a plan view of a can end blank from which a can bottom or can cover may be subsequently stamped showing the blank surface which will become the inside in the completed end; and 10

Fig. 4 is a perspective view of a can end or cover such as may be formed from the blank of Fig. 3.

The can of the present invention as shown in Fig. 1 may be made in the usual manner of sanitary double seamed cans. A lithographed can is shown. The can body blank designated by the numeral 11 in Fig. 2 which is used to produce this can is scored on its inner surface with short score lines 12 arranged adjacent the two long edges of 20 the blank. These score lines in the form disclosed are parallel and preferably do not extend quite to the edge.

Other parallel score lines 13 may also be cut in the can body adjacent the short edges of the 25 blank. These are shown as extending to the edge although they may stop short of the edge and in fact in many instances will not be used at all. One of the short edges is extended in the usual hook projection 14 at the ends of which are the 30 usual notches 15 this being an ordinary form of sanitary can body blank. The opposite short edge may be slit as at 16 such construction providing for the lock and lap side seam found in most sanitary cans of commerce.

The can ends which are the bottom and top of the can are first die cut or otherwise blanked from a metal sheet to produce an end blank 21 (Fig. 3). This blank may be scored adjacent its periphery in short radially disposed score lines 40 22. These score lines are cut on the inside surface, that is, on the surface which will become the inside of the end produced from the blank.

The can body blank 11 is brought into its tubular can body shape in the usual manner as by 45 rolling or bending and the desired edge hooks are bent to include the projection 14 and the part of the blank edge on the opposite side between the slits 16. This bending is done in one direction only and does not amount to a flexing of the 50 metal. The blank edges including the score lines 13 are thus shaped without in any way cracking or breaking the metal at the score lines.

A can body side seam 25 thus results and for most products the seam parts are subsequently 55

soldered. It will be obvious that where a full lap soldered side seam is used there will be no bending of blank edges in the scored areas 13.

The tubular can body is then flanged in the usual manner at its top and bottom. The bending of the metal incident to such flanging takes place in the region containing the score lines 12. This is a straight bending action in one direction and is in no way a flexing of the metal. There is, therefore, no cracking or breaking of the body wall.

The bottom for the can which may be drawn or otherwise shaped from an end blank 21 (Fig. 3) is then double seamed on the lower end of the can body as shown at 26 in Fig. 1. When the can end is drawn and this applies equally to both bottom and cover for the can, the peripheral edge of the blank is bent and shaped into the usual cupped and annular flange 27 (Fig. 4) leaving a central panel 28. In such shaping action there is no flexing of the metal but a bending in one direction, the score lines 22 not being broken or cracked in this operation.

In the double seaming of the end flange and the body flange the flanged parts are interlocked together in the usual manner and this further bends the can end and can body walls in the regions of the respective score lines 22 and 12 but this is merely further bending the scored parts in the same direction and there is no unbending or flexing action.

The can with its bottom end securely attached may then be used in the regular way, that is, it is filled with its contents and a cover (Fig. 4) may then be double seamed on the top of the can to fully seal it. This is the same procedure as in double seaming the bottom and the score lines 22 are brought partly into the double seam as shown at 29 in Fig. 1.

40 The can is provided with a label which identifies the product, this label usually being lithographed on the body wall as at 31 but it may also be on either end. Such a label for the top end is shown at 32 (Figs. 1 and 4).

45 When a substitution for the contents of a can is made it is first necessary to gain entrance to the can. Since the party making the substitution does not want to leave a record of the act but does want to remove the original contents from the can and replace it with something else, he effects admission into the can at a seam, either reshaping any bent parts or in most cases unbending the double seam, cutting away the end and thence resealing by using another end. Obviously a hole cannot be cut in the can and then patched after the substitution as this could not be done without the patch showing.

By scoring the various portions of the can at the seams as is herein shown and described, any 60 attempt to make an opening into the can at any seam part is completely frustrated. The scored areas while permitting the usual can manufacture which includes bending of the various parts in one direction, quickly break through where the reverse or unbending of the seamed parts is practiced. Thus wherever an attempt is made to provide an opening in the can the inherent accompanying flexing of the can wall at the place of opening breaks through and destroys that can 65 for further use.

While the drawing illustrates the scoring as located in both the side seam and the end seams of the can and in the end walls as well as in the body walls, in most cases the score lines 12 in the 70 body wall will effectively prevent that kind of

tampering which is prevalent at the present time.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof. 10

I claim:

1. A single service tamper-proof container formed to prevent undetected substitution of the container contents which comprises, a can body having a weakened score line cut in the interior surface of the body wall one end of said score line terminating adjacent an edge of said body, and a can end interengaged with said body in a seamed joint, said score line being incorporated in said seamed joint and insuring fracture of the body wall at the seam in the event that the can body and can end connection is disturbed as when attempting to open and reclose said container at its seamed joint. 15

2. A single service tamper-proof container formed to prevent undetected substitution of the container contents which comprises, a can body having a plurality of weakened score lines cut in the interior surface of the body wall one end of each score line terminating adjacent an edge of said body, and a can end interengaged with said body in a seamed joint which includes a part of said score lines, said score lines insuring fracture of the body wall material at the area thereof and at the seam in the event that the can body and can end connection is disturbed by an unbending of the body wall as when attempting to open and reclose said container at its seamed joint. 35

3. A single service tamper-proof labelled container formed to prevent undetected substitution of the container contents which comprises, a can body having a plurality of weakened score lines cut in the interior surface of the body wall and extending at an angle to the edge of said body, and a can end interengaged with said body in a seamed joint which partially encloses said score lines, said score lines insuring fracture of the body wall material at the area thereof and at the seam in the event that the can body and can end connection is disturbed as when attempting to open and reclose said container at its seamed joint. 45

4. A sheet metal single service tamper-proof lithographed container formed to prevent undetected substitution of the container contents which comprises, a can body having a lithographed label on its exterior surface and weakened score lines cut in its interior surface said score lines extending inwardly from the end edges of said body, and can ends interengaged with the body edges in seamed joints, said score lines being incorporated in said seamed joints and insuring fracture of the body wall at the seams and mutilation of said lithographed label in the event that the can body and can end connections are disturbed as when attempting to open and reclose the container at a seamed joint. 55

5. A single service tamper-proof lithographed container formed to prevent undetected substitution of the container contents which comprises, a can body having a lithographed label on its exterior surface and weakened score lines cut in its interior surface, said score lines extending inwardly from an end edge of said body, and a can cover having a lithographed label on its ex- 60

75

terior surface and weakened score lines cut in its interior surface which extend inwardly from its peripheral edge, said cover edge being inter-engaged with the body edge in a seamed joint in which said score lines are incorporated, said score lines insuring fracture of the can body and cover wall material in the area of said score lines with consequent mutilation of said lithographed labels in the event that the can body and can end 10 connections are disturbed as when attempting to open and reclose the container at its seamed joint.

6. A sheet metal single service tamper-proof lithographed container formed to prevent undetected substitution of the container contents which comprises, a can body having a side seam 15 and also having a lithographed label on its ex-

terior surface and weakened score lines cut in its interior surface adjacent its top and bottom edges and extending into its side seam, said score lines extending inwardly from the end edges of said body and from the edges which are enclosed in 5 said side seam, and a can bottom and a can cover interengaged with the body edges in seamed joints in which said score lines are embodied, said score lines insuring fracture of the body wall material at the seams in the area of said score 10 lines with consequent mutilation of said lithographed label in the event that the can body and can end connections are disturbed as when attempting to open and reclose the container at a seamed joint.
